ATTORNEY

UNITED STATES PATENT OFFICE.

OTTO F. BECKER, OF NEW YORK, N. Y.

HAIRPIN.

Application filed November 19, 1925. Serial No. 69,950.

This invention relates to hair pins and particularly to devices of this class provided with means for retaining the pin against accidental displacement from the hair when in use; and the object of the invention is to provide a hair pin of the class and for the purpose specified, comprising a hair pin body proper and a part movably mounted in connection with said hair pin proper and cooperating with the shanks of the pin for engaging a predetermined amount of hair and locking the same within and between the separate parts of the pin; a further object being to provide the movable part of the pin with ornamental means, which also functions to conceal or substantially conceal the hair pin proper, as well as the movable part thereof; and with these and other objects in view, the invention consists in a hair pin of the class and for the purpose specified which is simple in construction and operation, and efficient in use, and which is constructed as hereinafter described and claimed.

The invention is fully disclosed in the following specification, of which the accompanying drawing forms a part, in which the separate parts of my improvement are designated by suitable reference characters in each of the views, and in which:

Fig. 1 is a face view of one form of hair pin made according to my invention.

Fig. 2 is a side edge view of the pin shown in Fig. 1 with the movable part shown in different position in full lines.

Fig. 3 is a section on the line 3—3 of Fig. 2.

Fig. 4 is a view similar to Fig. 1 but showing a modified form of pin.

Fig. 5 is a side edge view of the pin shown in Fig. 4.

Fig. 6 is a view similar to Fig. 4 showing another modification; and,

Fig. 7 is a side edge view of the structure shown in Fig. 6.

In Figs. 1 to 3 inclusive, I have shown one form of hair pin comprising a hair pin body 10 of conventional general form, the crosshead of the pin in the construction shown, being twisted into spiral arrangement as seen at 11 to form a tubular bearing and support for a lock member 12, the crosshead of which is mounted in the bearing 11 or the crosshead of the pin 10. The side portions of the member 12 project in U-fashion, and the ends 13 of said side por-

tions terminate in hook-shaped form as clearly seen in Fig. 2 of the drawing. The member 12 is pivoted to the crosshead or bearing 11 of the pin 10, and in the use of the pin, the hair pin body proper 10 is inserted into the hair in the usual manner with the member 12 in the position shown in Fig. 1, and indicated in dotted lines in Fig. 2. After the pin has been placed in proper position, the member 12 is swung upon the pivot 11 into the position shown in full lines in Fig. 2, in which operation, a part of the hair adjacent the crosshead portion of the pin 10 proper, enters the loops 14 formed within the hook-shaped ends 13; and this hair so gathered, is clamped between the side portions of the member 12 and the hair pin 10 adjacent the crosshead end 11 thereof at the point 15, indicated in Fig. 2 of the drawing. The side portions of the member 12 are preferably recessed to engage the shank of the pin 10 to provide a lock engagement between the separate parts as seen at 16 in Fig. 3 of the drawing.

From the foregoing, it will be apparent that when the member 12 is moved into the full line position shown in Fig. 2, the pin is retained against displacement from the hair in the clamping of the hair between the separate parts of the hair pin at the point 15. When it is desirable to release the pin from the hair, the member 12 is returned to the position shown in dotted lines in Fig. 2, and the hair previously grasped is released in this operation, and the hair pin may then be readily removed from the hair without trouble.

It will be understood that the device shown in Figs. 1 to 3 inclusive will be preferably made of metal, but any desirable material may be employed such as the usual materials employed in the construction of hair pins, as for example, celluloid. In Figs. 4 and 5 of the drawing, I have shown a modified form of hair pin which might readily be constructed from celluloid or similar material, or made from metal if desired. In this construction, 17 represents the pin proper which is provided at the crosshead end with a sleeve like bearing 18 forming a keeper and pivot for a lock member 19, which in the construction shown, is in the form of a closed loop, the pivoted end portion of which has converging side members 20, the ends of which are extended laterally as seen at 21 and join the side por-

- tions of a V-shaped end member 21 which is offset with relation to the pivoted end of the member 19 to form a substantial hook end for engagement with the hair in the use
 5 of the pin, to bring the hair between the side portions 20 of the member 19 and the shanks of the pin 17 at the point 22, Fig. 5.

The use of the device shown in Figs. 4 and 5 will be precisely the same as that of the
 10 use of the device shown in Figs. 1 to 3 inclusive, the distinctive difference between the devices being that the hook member 21 is closed while the hook ends 13 are open, and the pivot of the lock member 19 is different
 15 from the pivot of the lock member 12.

In Figs. 6 and 7, I have shown another modification in which I employ in connection with a pin structure such as shown in Figs. 4 and 5, an ornamental device 23 of
 20 any kind or class, such for example as a barrette. This device 23 is mounted upon and secured to the lock member 19 or the side portions 20 thereof as clearly seen in Fig. 7 of the drawing. The device 23, in addition
 25 to providing ornamentation for the hair, also operates to conceal or partially conceal the hair pin 17, and the lock member 19, when the device is in use.

It will also be apparent that my improved
 30 hair pin construction may be employed for the purpose of supporting head or hair decorative devices of any kind or class in connection with the hair, in addition to the utility of said device as a hair pin; and while
 35 I have shown certain details of construction for carrying my invention into effect, it will be apparent that I am not necessarily limited to the several structural details herein shown and described, and various changes therein
 40 and modifications thereof may be made within the scope of the appended claims without departing from the spirit of my invention or sacrificing its advantages.

Having fully described my invention,
 45 what I claim as new and desire to secure by Letters Patent, is:—

1. A hair pin, the crosshead portion of which is provided with a cylindrical keeper, fashioned from the material thereof, a lock member coupled with said pin by said keeper, said lock member being movable with respect to the pin for engaging and retaining a predetermined amount of hair within and between said member and pin.
2. A hair pin, the crosshead portion of which is provided with a cylindrical keeper fashioned from the material thereof, a lock member coupled with said pin by said keeper, said lock member being movable with respect to the pin for engaging and re-

taining a predetermined amount of hair within and between said member and pin, and said lock member having ornamental means.

3. A hair pin, the crosshead portion of which is provided with a keeper, a lock member rotatably mounted in connection with the keeper of the pin and the projecting portion of which is hook-shaped in form and adapted to be passed between the side members of the hair pin adjacent the crosshead and to frictionally engage said side members to retain the lock member against accidental displacement.

4. A hair pin, the crosshead portion of which is provided with a keeper, a lock member rotatably mounted in connection with the keeper of the pin and the projecting portion of which is hook-shaped in form and adapted to be passed between the side members of the hair pin adjacent the crosshead and to frictionally engage said side members to retain the lock member against accidental displacement, and said lock member when in operative position being adapted to firmly engage a body of hair positioned between the same and the side members of the pin and to lock the pin against displacement from the hair.

5. A hair pin, the crosshead portion of which is fashioned to form a cylindrical bearing, a lock member comprising side members joined at one end in a hook-shaped portion and the other ends of said side members engaging said bearing to permit of rotation of the lock member relatively to the crosshead of the pin, and the side portions of the lock member being adapted to frictionally pass within and between the side members of the pin to retain said lock member against accidental displacement when in operative position.

6. A hair pin, the crosshead portion of which is fashioned to form a cylindrical bearing, a lock member comprising side members joined at one end in a hook-shaped portion and the other ends of said side members engaging said bearing to permit of rotation of the lock member relatively to the crosshead of the pin, the side portions of the lock member being adapted to frictionally pass within and between the side members of the pin to retain said lock member against accidental displacement when in operative position, and a part independent of the hair pin and secured to said lock member.

In testimony that I claim the foregoing as my invention I have signed my name this 17th day of Nov. 1925.

OTTO F. BECKER.
